COMBINED STORAGE AND CARRYING CONTAINER

Everett R. Yonce, 464 42nd St., Oakland, Calif. 94609

Filed Apr. 16, 1971, Ser. No. 134,926

Term of patent 14 years

Int. Cl. D3—01

U.S. Cl. D87—1

FIG. 4

FIG. 1

FIG. 2

FIG. 3

FIG. 1 is a top perspective view of a combined storage and carrying container showing my new design;

FIG. 2 is a bottom perspective view showing the side and end not seen in FIG. 1;

FIG. 3 is a top plan view; and

FIG. 4 is a fragmentary sectional view of the upper portion taken on line 4-4 of FIG. 1.

I claim:

The ornamental design for a combined storage and carrying container, substantially as shown.
